UNITED STATES PATENT OFFICE.

CYRIL A. BRIGHAM, OF EAST ORANGE, NEW JERSEY, ASSIGNOR TO BRANDES LABORATORIES, INC., OF NEWARK, NEW JERSEY, A CORPORATION OF NEW JERSEY.

SOUND-REPRODUCING APPARATUS.

Application filed November 2, 1926. Serial No. 145,808.

My invention relates broadly to electromagnetic sound reproducers and more particularly to a construction of electromagnetic driver and conical shaped sound reproducing diaphragm.

One of the objects of my invention is to provide a simplified construction of cone shaped sound reproducing diaphragm with an electromagnetic driving member secured thereto.

Another object of my invention is to provide a construction of bridle or connecting means between the electromagnetic driving element and a cone shaped sound reproducing diaphragm.

Another object of my invention is to provide a link connection between a conical shaped sound reproducing diaphragm and electromagnetic driving element which connection is independent and remote from the apex of the conical shaped sound reproducing diaphragm.

Other and further objects of my invention will be understood from the specification hereinafter following by reference to the accompanying drawings in which:

Figure 1 is a front view illustrating the assembly of the sound reproducing diaphragm and electromagnetic driving element of my invention; Fig. 2 is a plan view of the sound reproducing diaphragm showing the connection of the electromagnetic driving element thereto, the diaphragm being partially broken away and illustrated in section; Fig. 3 is a cross-sectional view taken through the electromagnetic driving mechanism and sound reproducing diaphragm of my invention; Fig. 4 is a lateral cross-sectional view of the sound reproducer of my invention taken on line 4-4 of Fig. 3; and Fig. 5 is a perspective view showing the parts of the bridle element by which connection is established between the electromagnetic driving element and the sound reproducing diaphragm.

My invention relates particularly to the class of electromagnetic sound reproducers illustrated in my copending application, Serial Number 135,192, filed September 13, 1926.

Referring to the drawings in detail, I have illustrated the sound reproducer as comprising a panel 1 in which the cone shaped sound reproducing diaphragm 3 is

arranged to float, the peripheral edge 4 of the sound reproducing diaphragm being connected to the plate 1 by means of an annular strip 2. The sound reproducing diaphragm is substantially in the form of a frustum of a cone terminating at a small diameter 5. Embracing the small diameter 5 of the cone I provide a pair of semi-circular members 6 and 7 which conform to the peripheral edge 5 of the cone with strip-like extensions 6^a, 6^b and 7^a, 7^b extending in a plane 60 passing through the axis of the cone. The driving mechanism of the cone consists of a pair of windings 10 and 11 which are secured to opposite sides of the flat coil support 8. The coil support 8 is constructed of 70 insulating material which is of extremely light weight by reason of cut away portions 9. A pair of extensions or arms 8^a and 8^b are formed on the coil support 8 with their ends cut away to conform to the shape 75 of the sound reproducing diaphragm 3 and formed in such manner that the strip-like extensions, 6^a, 6^b, 7^a and 7^b are arranged to grip opposite sides of the extensions 8^a and 8^b forming a rigid connection between the 80 coil 5 and the cone-shaped diaphragm. The spider member 12 is suspended from the strip member 14 which is in turn attached to the frame 15 of the loud speaker. The 85 loud speaker is provided with an electromagnetic system including sets of pole pieces 16 and 17 which may be provided with face plates 18 and 19 for rendering the reproduction more uniform as described in my aforementioned application. The strip member 12 connects with the coil support 8 as represented at 21 and 22 in such 90 manner that the sound reproducing diaphragm 4 and the windings 10 and 11 substantially float between the frame 1 and the strip member 14. It will be observed that 95 the windings 10 and 11 are free to move in a lateral direction between the sets of pole pieces without inertia, the coils being confined in a path parallel to the pole pieces and at right angles to the magnetic lines 100 of force passing between the pole pieces. The bridle connection between the small diameter of the cone shaped sound reproducing diaphragm and the coil support insures 105

the efficient transfer of mechanical vibrations from the coil support to the sound reproducing diaphragm.

The preferred embodiment of my invention described in the drawings has been found to be extremely practical and efficient in operation, but I desire that it be understood that modifications may be made and that no limitations upon my invention are intended other than are imposed by the scope of the appended claims.

What I claim as new and desire to secure by Letters Patent of the United States is as follows:

- 15 1. A sound reproducer comprising a conical shaped sound reproducing diaphragm, an electromagnetic driving mechanism including a flat coil structure and a connection between said conical shaped sound reproducing diaphragm and said flat coil structure comprising a bridle encircling said conical shaped sound reproducing diaphragm and secured at diametrically opposite points to said flat coil structure.
- 20 2. A sound reproducer comprising a sound reproducing diaphragm substantially in the shape of the frustum of a cone, an apertured plate member encircling the peripheral edge of said sound reproducing diaphragm at the largest diameter thereof, means connecting the peripheral edge of said sound reproducing diaphragm with said plate member, an electromagnetic driving mechanism including a laterally movable element, means for suspending said laterally movable element at one end thereof for free movement in the direction of said sound reproducing diaphragm and a connection between two separated points on said laterally movable element and said sound reproducing diaphragm

whereby vibrations imparted to said laterally movable element may be transferred to said sound reproducing diaphragm.

3. A sound reproducer comprising a sound reproducing diaphragm substantially in the shape of the frustum of a cone, an electromagnetic driving mechanism including a movable coil structure located along the axis of said sound reproducing diaphragm, a connection between separated points on said movable coil structure and separate points on said sound reproducing diaphragm on diametrically opposite sides of the center thereof, and means for flexibly suspending the peripheral edge of said sound reproducing diaphragm and one end of said movable coil structure whereby vibrations imparted to said movable coil structure may be transferred to said sound reproducing diaphragm.

4. A sound reproducer comprising a sound reproducing diaphragm substantially in the shape of the frustum of a cone, an electromagnetic driving mechanism including an element movable in the direction of the axis of said sound reproducing diaphragm, means for flexibly suspending said movable element and said sound reproducing diaphragm, a pair of arms extending from said movable element and engaging said sound reproducing diaphragm at diametrically opposite points thereon and a pair of semi-circular strip members secured to said sound reproducing diaphragm and connecting opposite sides of said arms whereby vibrations initiated in said movable element may be transferred to said sound reproducing diaphragm.

In testimony whereof I affix my signature.
CYRIL A. BRIGHAM.
